UNITED STATES PATENT OFFICE.

ERNST BARLACH, OF RENDSBURG, GERMANY.

PENHOLDER AND PENCIL-POINT PROTECTOR.

SPECIFICATION forming part of Letters Patent No. 639,499, dated December 19, 1899.

Application filed May 16, 1899. Serial No. 717,082. (No model.)

To all whom it may concern:

Be it known that I, ERNST BARLACH, a subject of the Emperor of Germany, residing at Rendsburg, in the Province of Schleswig-Holstein and Kingdom of Prussia, Germany, have invented certain new and useful Improvements in Penholders and Pencil-Point Protectors; and I do hereby declare the following to be a full, clear, and exact description of the invention, such as will enable others skilled in the art to which it appertains to make and use the same.

My invention relates to a device adapted to be slid upon an ordinary penholder or pencil and used as a means for holding a pen-nib upon the said holder or pencil in order that such nib may be employed for writing in the usual way or fixed upon a pencil in such a manner as to provide a firmer grip between the fingers and pencil when in use and as a protector for the point of the said pencil when not in use.

The said device is shown in the accompanying sheet of drawings, in which—

25 Figure 1 is an enlarged side or elevational view of the said device mounted upon a penholder or pencil, Fig. 2 being a section of Fig. 1 upon the line X X. Fig. 3 is an end view of Fig. 1 with the pencil or penholder in section. Fig. 4 is a further-enlarged view of either end of the said device when detached from the said holder or pencil.

30 My invention consists of a cylinder or sleeve A of elastic material, such as india-rubber or the like, upon the inside of which are any number of strips of flat metal B, preferably six, as in Figs. 1 and 3, or four, as in Fig. 4, the said metallic strips being so much longer than the cylinder or sleeve A as to permit

their ends to be bent over the ends and turned 40 down upon the outer face of A, as shown, and be thereby fastened thereto. The diameter of the sleeve A is such that it requires a little force in slipping it over an ordinary pencil or penholder, the holder being thereby held in 45 position when placed upon the same. The said device when placed upon an ordinary pencil may serve to provide a firmer grip for the fingers when in use, and as a protector for the point of the said pen when not in use. 50 The said cylinder or sleeve A would be preferably so molded during its manufacture that when not mounted upon a penholder or pencil, as in Figs. 1, 2, and 3, would collapse after the manner shown by the view Fig. 4, when 55 if the number and arrangement of the metallic strips B be such as to be placed against each other, as in Fig. 4, the heel of a pen-nib may be inserted between the superposed plates B and be therein retained by the grip of the 60 said plates, thus permitting the device to be used alone as a penholder.

Having now particularly described and ascertained the nature of my said invention and in what manner the same is to be performed, 65 I declare that what I claim is—

In a penholder and pencil-point protector, the combination with a flexible cylindrical portion; of a plurality of flat bars of metal passing through the said cylindrical portion 70 and bent back upon the outer surface of the same, substantially as described.

In testimony whereof I have affixed my signature in presence of two witnesses.

E. BARLACH.
